United States Patent

Des. 238,153
Patented Dec. 23, 1975

238,153

LEVEL TOOL

Vern H. Johnson and Robert G. Harms, Cheyenne, Wyo.,
assignors to Loyd Walters, Pine Bluffs, and Donald
Kunau, Cheyenne, Wyo., fractional part interest to
each

Filed Aug. 29, 1974, Ser. No. 501,700

Term of patent 14 years

Int. Cl. D10—05

U.S. Cl. D10—69

FIG. 1.

FIG. 2.

FIG. 3.

FIG. 4.

FIG. 6.

FIG. 7. FIG. 8.

FIG. 9.

FIG. 10.

FIG. 11. 13 ← → 14 ← 15 ← 14

FIG. 12. 13 ← → 14 ← 15 ← 14

FIG. 14.

FIG. 13.

FIG. 15.

FIG. 1 is a top left perspective view of a level tool showing our new design;

FIG. 2 is a top plan view thereof;

FIG. 3 is a rear side elevational view thereof;

FIG. 4 is a bottom plan view thereof;

FIG. 5 is a left end elevational view thereof;

FIG. 6 is a right end elevational view thereof;

FIG. 7 is a transverse cross-sectional view thereof as taken from line 7—7;

FIG. 8 is a transverse cross-sectional view thereof as taken from line 8—8;

FIG. 9 is a side elevational view of another embodiment of our new design of FIG. 1;

FIG. 10 is a top plan view of FIG. 9;

FIG. 11 is an opposite side elevational view of FIG. 9;

FIG. 12 is a bottom plan view of FIG. 9;

FIG. 13 is a transverse cross-sectional view as taken from line 13—13 of FIG. 11;

FIG. 14 is a transverse cross-sectional view as taken from line 14—14 of FIG. 11;

FIG. 15 is a transverse cross-sectional view as taken from line 15—15 of FIG. 11.

We claim:

The ornamental design for a level tool, as shown and described.
